UNITED STATES PATENT OFFICE.

DOSIER H. MOSTELLER, OF SAN FRANCISCO, CALIFORNIA.

SYSTEM FOR SUPPLYING OIL UNDER WATER-PRESSURE.

SPECIFICATION forming part of Letters Patent No. 761,091, dated May 31, 1904.

Application filed June 25, 1903. Serial No. 163,054. (No model.)

To all whom it may concern:

Be it known that I, DOSIER H. MOSTELLER, a citizen of the United States, residing at San Francisco, in the county of San Francisco and State of California, have invented certain new and useful Improvements in Systems of Supplying Oil under Water-Pressure, of which the following is a specification.

My invention relates to an improved system of piping for supplying oil under water-pressure to oil-burners for use in ranges, furnaces, or the like.

The object of my invention is to provide such a system by means of which the oil can be replenished without interfering in any way with the pressure or with the supply of oil to the range, thus enabling the fire to continue undiminished.

A further important improvement is to provide means whereby the air which is removed from the tank in filling it with oil and which has a strong and unpleasant odor can be conducted in a convenient manner to the sewer, so that the odor will not escape into the building.

A further important feature of my invention is to provide means whereby the reservoirs for the oil may be inclosed in brick-work or the like protective material, while at the same time permitting free control of the oil and water in the tanks and enabling at all times the condition of the tanks to be ascertained.

My invention therefore resides in the novel construction, combination, and arrangement of parts for the above ends hereinafter fully specified, and particularly pointed out in the claims.

In the accompanying drawings, Figure 1 is a perspective view of my improved system. Fig. 2 is a horizontal section of a modification in which the system is inclosed in brickwork.

Referring to the drawings, 1 represents the oil-supply pipe, which may extend through the sidewalk, and is provided at the top with a coupling 2 for the purpose of connection with the oil-wagon to fill the tank with oil.

3 represents the oil-tanks, which are provided in duplicate, so that one can be used while the other is being filled. Directly to

said tanks lead pipes 4, which extend upward and then horizontally forward and are connected near their front end with vertical pipes 5, one of which is connected directly with the oil-supply pipe 1 and the other indirectly by means of a horizontal pipe 6. Stop-cocks 7 are interposed in the short vertical pipes, so as to allow of the filling of said pipes from said tanks as may be desired. Said oil-supply pipes are continued forward and connect with the feed-pipe 8, which leads to the range or furnace or other heating medium. In the short forwardly-extending ends are stop-cocks 9 for shutting off either or both of said tanks from the range or furnace.

10 represents the water-supply pipe, which is fed with water from the city main or any other source of water under pressure. If necessary, a cistern may be provided at a suitable height above the water-supply pipe to give the desired pressure. Said water-supply pipe has a check-valve 11 therein. In order also to insure a supply of water under pressure even in case of the said water being turned off temporarily, I provide an auxiliary water and compressed-air tank 12, containing a sufficient supply of water to feed either of the tanks 3 with water and also a supply of compressed air providing the desired pressure, which compressed air may be obtained by means of a small pump 13, attached to said compressed-air tank. It will readily be seen that if the usual supply of pressure-water is cut off the auxiliary tank may be used to furnish the desired pressure by opening the cock 14 below said tank.

The pressure-water flows through the two pipes 15, controlled by stop-cocks 16, into the vertical pipes 17, which extend downward and then horizontally to a point underneath the tanks and then into said tanks. By a suitable choice of the stop-cocks 16 the water can be caused to enter either tank at will. Above said horizontal pipes 15 the vertical pipes 17 are continued to form discharge-pipes having stop-cocks 18 therein, and at the top said discharge-pipes are connected to a discharge-conduit 19, leading to the sewer-pipe 20.

The quantity of oil in the tank can be ascertained at any time by inspection of the

gages 21, connected to pipes 22, which are connected to the tanks at the top and at a point near the bottom, as shown.

- I also provide means for allowing of a vent 5 of the air from the tanks in filling the same with oil, said vents comprising the pipes 23, which extend horizontally forward from the top of the tank and are connected by a horizontal pipe 24, one of said pipes then leading 10 vertically downward, as shown at 25, into the discharge-conduit 19. Said pipes 23 have stop-cocks 26 for shutting off said pipes when desired. Sight-gages 27 28 are provided in the pipes 25 19.
- 15 The operation of the apparatus is as follows: Supposing that one tank is full of oil and the other tank is being exhausted and it is now desired to replenish the latter and to commence using the full tank for the purpose of 20 feeding oil to the range or furnace, the first step is to admit the water-pressure to the full tank by opening the corresponding stop-cock 16, if it is not already open. The next step is to simultaneously close the stop-cock 9 in 25 the feed-pipe from the empty tank and open the stop-cock 9 in the feed-pipe from the full tank, thus maintaining the supply of oil under pressure to the range or furnace. Now proceeding to fill the empty tank with oil, this 30 is accomplished as follows: First the water-pressure is shut off from the empty tank by closing the stop-cock 16. Next the discharge-pipe from said empty tank is opened by opening the stop-cock 18. This allows the water 35 to run out of the empty tank into the sewer. While the water is running out, oil may be admitted to the empty tank through the oil-supply pipe 1 by means of the pipes 4 5, the stop-cock being opened for that purpose. 40 Also the stop-cock 26, which controls the air-escape pipe, is opened to allow the air to escape into the discharge-conduit and thence to the sewer, as already explained. The water runs out of the tank, and by inspection 45 of the gage 28 it is ascertained when the water has been completely removed from the tank. Then the stop-cock 18 is closed to prevent any further escape of oil. Oil is still supplied to the tank, which is being filled 50 until a sufficient quantity has been supplied thereto, care being taken that no oil remains in the pipes above the tank. The stop-cock 7 is then closed. Pressure-water is now admitted by opening the cock 16. This immediately forces any air from the top of the 55 tank through the air-escape pipe, and the gage 27 in this pipe is watched until it is seen that oil begins to flow therethrough, so that no air is left in the tank, this being extremely important to avoid, for any compressed air left

in the tank would blow the fire out. The stop-cock 26 in the air-escape pipe is now closed, and the tank is ready for further use when required.

In some places there are municipal and underwriters' regulations requiring the tanks to be inclosed—as, for instance, with a brick wall of a certain thickness around and above the tanks. It will be seen that my improved system is well adapted for compliance with such regulations. The pipes are brought from the tanks through the wall, (shown at 30,) and the gages are inclosed in a recess or box 31, formed in the front of the wall, having an iron door or shutter 32, as shown, which may be 75 opened for the purpose of inspection of the gages at any time. It will also readily be seen that this system allows of the tanks being buried at a considerable depth below the ground, if desired, the pipes being then continued to a considerable height for inspection and operation and suitable means being provided for ascertaining the condition of the tanks.

While I have herein shown a duplicate system of tanks, there are important features of my invention—as, for instance, the escape of the air from the tank into the sewer—which are not confined to a duplicate system, but can also be used in connection with a single tank.

I claim—

1. In an apparatus of the character described, the combination of a pair of oil-tanks, a discharge-pipe connected with the bottoms of said tanks for discharging water therefrom, a vent-pipe leading from the top of each tank and connected to said discharge-pipe, whereby the noxious gases from said tanks are carried off by said discharge-pipe, and sight-gages in said connections, substantially as described.

2. In an apparatus of the character described, the combination of a pair of oil-tanks, a discharge-pipe connected with the bottoms of said tanks for discharging water therefrom, a vent-pipe leading from the top of each tank and connected to said discharge-pipe, whereby the noxious gases from said tanks are carried off by said discharge-pipe, sight-gages in said connections, a pressure water-tank connected to said pair of oil-tanks, and means for forcing air into the upper portion of said latter tank, substantially as described.

In witness whereof I have hereunto set my hand in the presence of two subscribing witnesses.

DOSIER H. MOSTELLER.
